H. WOHLGEMUTH

SCAFFOLD ROPE CLAMP

Filed Sept. 15, 1924

UNITED STATES PATENT OFFICE.

HUGO WOHLGEMUTH, OF NEW YORK, N. Y.

SCAFFOLD-ROPE CLAMP.

Application filed September 15, 1924. Serial No. 737,778.

To all whom it may concern:

Be it known that I, HUGO WOHLGEMUTH, citizen of the United States, residing at New York city, in the county of New York and 5 State of New York, have invented certain new and useful Improvements in Scaffold-Rope Clamps, of which the following is a specification.

This invention relates to a clamp for scaffold ropes, that is used to bind together the various reaches of a scaffold supporting rope, thereby locking the rope against movement.

The invention has for an object to provide a novel and simple device of this sort that can be readily applied to the rope, and which will not be liable to damage the latter.

For further comprehension of the invention, and of the objects and advantages thereof, reference will be had to the following description and accompanying drawing, and to the appended claims in which the various novel features of the invention 25 are more particularly set forth.

Fig. 1 of the drawing is a face view of my improved rope clamp.

Fig. 2 is a transverse sectional view thereof taken along the line 2—2 of Fig. 1.

Fig. 3 is a similar view to Fig. 1 but showing a modification.

Fig. 4 is a longitudinal sectional view taken on the line 4—4 of Fig. 3.

Fig. 5 is a transverse sectional view taken 35 on the line 5—5 of Fig. 3.

As here embodied my improved clamp comprises a rectangular frame 10 through one end of which a clamping screw 11 is threaded. The inner end of this clamping screw has a swivel engagement, as indicated 40 at 12 with a clamping crosshead 13 that is provided on its ends with T-shaped grooves 14 that engage over the sides of the frames 10. The outer end of the clamping screw 45 has a disk handle 16 fixed thereto for purposes of rotation.

At their adjacent sides the crosshead 13 and the end member 10' of the frame that is remote from the screw are suitably curved 50 as shown at 18 and 19 respectively to grip the rope. Pivoted as at 29 in recesses 30 in the crosshead 13 are the jaws 22 that are normally urged away from one another by the tension springs 25 attached at their ends 55 to upward projections from the jaws, the latter depending downward to engage the

rope. These jaws have their remote sides cammed or inclined as at 22 to form cams that are engaged by rollers 31 on the sides of the frame 10 when the crosshead 13 is 60 screwed inward, the jaws being thus compressed against the sides of the rope. The end member 10' of the frame is preferably made removable to permit of insertion of the rope therein, being here shown as 65 formed with bifurcated ends that straddle the diminished ends of the side members of the frame and are secured thereto by screws 26.

In the form of the invention shown in 70 Figs. 3 to 5 the crosshead 13 is formed at its ends with tongues 14 that project into guide grooves 15 in the sides of the frame 10. Instead of the jaws 22 I provide a pair 75 of arms or jaws 22' that are pivoted at one end as at 20 in recesses 21 in the said end member 10' and are adapted to project rearwardly, on opposite sides of the rope, to clamp thereagainst. The free or rear ends of 80 these arms project into apertures 23 in the crosshead 13, these apertures presenting cam walls 24 that bear on the ends of the levers and act to compress the same toward one another when the crosshead is moved forwardly by rotating the screw 11. The arms 22 are normally urged away from one another by the tension spring 25.

In this construction the inner portions of the spaces between the forked ends of the end member 10' form the recesses 21 above 90 referred to that receive the lever arms 22'.

My improved clamp acts to firmly grip the rope, without tendency to distort or injure the latter by squeezing it into flat shape, as will be apparent from the disposition of parts above described and illustrated in the drawing. When the screw 11 is rotated to move the clamping crosshead 13 forward, the jaw or lever arms 22 are also moved toward one another by reason of the walls 24 on the crosshead bearing on the inclined ends of the said arms, the arms presenting curved adjacent faces that engage the sides of the rope, the three reaches of the rope being thus all compressed together.

Having thus described my invention what I claim as new and desire to protect by Letters Patent of the United States is as follows:

1. A scaffold rope clamp comprising a rectangular frame, a clamping crosshead 110 slideable in said frame, and a pair of clamp-

ing levers pivoted in said frame, and means providing an operative connection between said crosshead and said levers whereby clamping movement of the crosshead im-
parts similar movement to the said levers, and a screw threaded through the frame and bearing on the said crosshead.

2. A scaffold rope clamp comprising a rectangular frame, a clamping crosshead slide-
able in said frame and formed with ap-
ertures adjacent its ends, a pair of lever arms
pivoted at one end to said frame and pre-
senting inclined free ends engaging in said
apertures whereby said lever arms are
moved toward one another when the said
crosshead is moved forward.

3. A scaffold rope clamp comprising a rectangular frame, a clamping crosshead
slideable in said frame and formed with
apertures adjacent its ends, a pair of lever
arms pivoted at one end to said frame and

presenting inclined free ends engaging in
said apertures whereby said lever arms are
moved toward one another when the said
crosshead is moved forward, the apertures
in said crosshead presenting cam walls
adapted to bear on the end of the lever
arms.

4. A scaffold rope clamp comprising a rectangular frame, a clamping crosshead slide-
able in said frame and formed with ap-
ertures adjacent its ends, a pair of lever arms
pivoted at one end to said frame and pre-
senting inclined free ends engaging in said
apertures whereby said lever arms are
moved toward one another when the said
crosshead is moved forward, and a screw
threaded through said frame and bearing
on said crosshead.

In testimony whereof I have affixed my
signature.

HUGO WOHLGEMUTH.
